Attorney

UNITED STATES PATENT OFFICE

GORDON E. ROEDDING, OF GRAND RAPIDS, MICHIGAN, ASSIGNOR TO GRAND RAPIDS BRASS COMPANY, OF GRAND RAPIDS, MICHIGAN, A CORPORATION OF MICHIGAN

LATCH

Application filed June 4, 1931. Serial No. 541,965.

The present invention relates to latches; and its object is, generally, to provide an improved latch for a door closure adapted to be tripped from retracted position by the closing movement of the closure; and more particularly, to provide parts of such a latch and combinations of such parts operating in an improved manner hereinafter appearing.

These objects are attained by, and the invention finds preferable embodiment in, the latch structure particularly described in the body of this specification and illustrated by the accompanying drawing, in which:

Figure 1 is a front elevational view of portions of a door closure and door jamb with a latch and its keeper mounted thereon respectively, the latch's bolt being indicated in its latching position;

Figure 2 is a horizontal sectional view thereof taken on line 2—2 of Figures 1 and 3;

Figure 3 is a vertical sectional view of portions of the same taken on line 3—3 of Figures 1 and 2;

Figure 4 is a free edge elevational view of the partly closed door closure with the latch thereon and an inner side view of the latch's keeper, its mounting screws being sectioned on line 4—4 of Figure 2; and

Figure 5 is a vertical sectional view of the latch taken on line 5—5 of Figure 2.

In the drawing is illustrated a latch mounted adjacent the free edge of a swingable door closure 1, and its keeper mounted on the edge of the jamb 2 of the door. The latch comprises a base member having a recessed body portion 3 mounted as by screws 4 on the inner side of the closure, and a hollow post portion 5 extending outwardly in the bore 6 through the closure, the spaced legs 7 of this post portion being seated at 8 in the body portion.

The body portion and the post portion have aligned bearings 9, 10 respectively in which is journalled a shaft 11 having on its outer end a handle 12 for turning it. The recess 13 of said body portion contains a flat latch bolt 14 into whose elongated slot 15 the flattened inner end 16 of the shaft extends, so that the bolt is carried by the shaft turnably therewith, and so that the bolt is tiltable on

the shaft axially thereof, i. e. in the plane in which lies the axis of the shaft.

A spring 17 is coiled about the shaft engaging at its upper end at 18 thereon and at its lower end engaging on the base at 19. This spring torsionally urges the shaft in the direction which turns the bolt to latching or operative position shown in Figure 5 and indicated in Figure 1. When however the handle 12 is turned toward the left-hand side of Figure 1 to open the closure, the bolt is thereby moved from such latching position (in which it is stopped by the stop 20) bearing on the surface 21 of the body portion 3 until the ledge 22 of said portion is reached, whereupon the spring, pressing in the shaft's axial direction, tilts the bolt toward the bottom of the recess 13 of said body portion and into retracted position in which it is held by the ledge 22 as shown in Figure 4. When the closure moves to closed position, the bolt's under edge 23 strikes the upwardly-inwardly inclined surface 24 of the latch's keeper 25 mounted as by screws 26 on the edge 27 of the door jamb. This closing movement of the closure pushes the bolt off the ledge 22, and as such closing movement continues, the bolt rides upwardly on the keeper's surface 28 to operative or latching position.

The invention being intended to be pointed out in the claims, is not to be limited to or by details of construction of the particular embodiment thereof illustrated by the drawings or hereinbefore described.

I claim:

1. A latch for a door closure comprising: a base having a ledge; a shaft journalled on the base; a latch bolt carried on the shaft turnably therewith to latching position and tiltable axially thereof; a spring coiled about the shaft, torsionally urging the same to turn the bolt to latching position, and in one position of the shaft tilting the bolt to retracted held position on the ledge; the latch having a keeper on which the retracted bolt strikes in the closure's closing movement to tilt the bolt from the ledge.

2. A latch for a door closure, having a bore therethrough, comprising: a base having a body portion mounted on the inner side of

the closure and a hollow post portion extending in the bore, the body portion having a ledge and said portions having aligned bearings; a shaft journalled in said bearings and having a handle on its outer end; a latch bolt carried on the shaft turnably therewith to latching position and tilttable axially thereof; a spring coiled about the shaft, torsionally urging the same to turn the bolt to latching position, and in one position of the shaft tilting the bolt to retracted held position on the ledge; the latch having a keeper on which the retracted bolt strikes in the closure's closing movement to tilt the bolt from the ledge.

3. A latch for a door closure comprising: a base having a recess and a ledge; a shaft journalled on the base having a flattened end; a latch bolt in said recess having a slot receiving said flattened end non-turnably but tiltably in the shaft's axial plane; a spring coiled about the shaft, torsionally urging the same to turn the bolt to latching position, and in one position of the shaft tilting the bolt to retracted held position on the ledge; the latch having a keeper on which the retracted bolt strikes in the closure's closing movement to tilt the bolt from the ledge.

In testimony whereof I have hereunto set my hand at Grand Rapids, Michigan, this 20 1st day of June, 1931.

GORDON E. ROEDDING.
